UNITED STATES PATENT OFFICE

HERBERT K. BAKER, OF DETROIT, MICHIGAN, ASSIGNOR TO PENN METAL COMPANY,
OF PARKERSBURG, WEST VIRGINIA, A CORPORATION OF MASSACHUSETTS

METHOD OF EXPANDING METAL LATH

Application filed April 24, 1929. Serial No. 357,643.

This invention relates to a method of expanding metal lath and has particular reference to the type of expansion involving the use of diverging expander arms or guides.

Generally considered, the objects of the invention include increased rate of production, simplification of the construction and operation of the apparatus employed and production of lath with the least possible strains, to the mesh work, which tend to result in a weak and easily broken finished product.

More specifically, I contemplate the employment of a pre-opening operation in order to facilitate the subsequent and complete expansion of the mesh work.

It is also an object of the invention to reduce the angle of divergence of the expander guides in order that the blanks may not be subjected to any sudden tearing strains during expansion and in order to simplify the driving mechanism for the rollers which feed the blanks through the diverging expander guides.

I also contemplate making the cooperating elements of the guides in such a manner and of such materials as to give them very great operating life and render them inexpensive and readily renewable.

How the foregoing objects and advantages are obtained together with others which are incident thereto, will be clear from a consideration of the following description taken with the accompanying drawings which illustrate the preferred embodiment of the invention and in which

Figs. 1a and 1b constitute a top plan view of apparatus suitable for accomplishing the pre-opening and expanding of the present invention;

Figs. 2a and 2b taken together form a side elevational view of the apparatus shown in Figs. 1a and 1b.

Fig. 3 is an enlarged sectional view taken thru certain parts of the pre-opening mechanism substantially as indicated by the line 3-3 of Fig. 2a;

Fig. 4 is an enlarged longitudinal section

thru the pre-opening mechanism taken as indicated by the line 4-4 of Fig. 1a;

Figs. 5 to 8 inclusive are somewhat diagrammatic views (taken as described hereinafter) of details of the pre-opening mechanism including sectional showings of certain of the guides with a blank therebetween;

Figs. 9 and 10 are sectional views of the expander guides taken as indicated by the lines 9-9 and 10-10 of Figs. 1a and 1b respectively;

Fig. 11 is a sectional view thru the delivery end of the apparatus of the present invention taken substantially as indicated by the line 11-11 of Fig. 1b;

Figs. 12 and 13 are face and sectional views, respectively, of a slotted and ribbed blank adapted to be expanded by the apparatus and according to the method of the present invention; and

Figs. 14 and 15 are face and sectional views, respectively, of a portion of a completely expanded sheet of lath.

Before describing in detail the method and apparatus herein disclosed, it should be understood that the invention is particularly concerned with the completion of what is now well known in the art as "high rib lath" the same having relatively high ribs or grooves formed in the unslotted strips extending longitudinally of the sheets between mesh work sections, in contradistinction to what is commonly called "flat rib lath" which is usually provided with very shallow beads extending longitudinally thru the unslotted strips of a sheet. It might also be observed that the relatively deep grooves of the former type of lath are provided primarily for the purpose of giving the sheet strength and rigidity while the very shallow beads of the latter type are commonly employed in order to provide means whereby the blanks may be guided thru and expanding mechanism.

In order that the method of the present invention may be more readily understood, reference should first be made to Figs. 12 to 15 inclusive, Nos. 12 and 13 of which illustrate the condition of the blank just

prior to the time of entering the mechanism of the present invention and Nos. 14 and 15 of which illustrate the lath after it has been delivered from the mechanism of the present invention in a completely expanded form. A method and apparatus for producing blanks of the type illustrated in Figs. 12 and 13 is disclosed in my copending application Serial No. 356,331, filed April 19th, 1929.

It will be observed from the figures just above noted that the blanks are provided with pairs of longitudinally extended slit areas, the slits being arranged to provide strands S which are arranged in staggered formation and which are interconnected by connecting bridges Z. The strands S are inclined longitudinally of the blank and the strands of adjacent areas or strips are oppositely inclined. Between the pairs of slit areas are unslotted strips X which are relatively wide and thru which extend the relatively shallow beads B. The beads B are adapted to be engaged and folded up into the relatively high ribs indicated at B' in Figs. 14 and 15 by means of the apparatus to be described hereinafter.

It is also to be noted at this point that angled grooves G extend longitudinally of the blank between the slit areas of each pair, the legs of the grooves G preferably extending substantially at right angles to each other and overlying or taking in a portion of the slit areas on either side. Note also that the beads B and the grooves G are arranged in alternate formation transversely of the sheet and that all of the grooves G project to one side or face of the sheet while the beads B project toward the other.

From inspection of the drawings, particularly Figs. 1a, 1b, 2a, 2b, 3 and 4, it will be seen that the form of apparatus for carrying out the process is mounted on a bed plate or table 16 which is suitably supported on uprights or standards 17.

The apparatus for accomplishing the pre-opening of the lath (see Figs. 1a, 2a, 3 and 4) includes the upper and lower cooperating sets of feeding rollers 18 and 19 respectively which are adapted to engage the relatively shallow beads B to start the blanks thru the apparatus and which are suitably mounted on shafts 20 and 21, the latter being journaled in supporting members 22 secured to 55 and extending upwardly from the bed plate 16. Note that the lower shaft 21 is journaled directly in the members 22 and that the upper shaft 20 is journaled therein indirectly, so to speak, by means of bearing blocks 23 mounted for vertical movement between jaws opening from the top edges of the members 22. Bracket members 24 bridge the jaws and are provided with adjusting bolts 25 for securing the blocks 23 in position to bring the working surfaces of the up-

per and lower cooperating rollers 18 and 19 into position for gripping and feeding the blanks as they are fed into the apparatus. The manner in which the blanks are gripped and fed by the rollers 18 and 19, just described, as well as by those to be described hereinafter, is clearly illustrated in Figs. 5 to 8 inclusive.

Extending forwardly from the working surfaces of the rollers 18 and 19, I have provided cooperating pairs of upper and lower guides for engaging the beads B and guiding the blanks forwardly until they are engaged by other rollers which perform the folding up operation. These guides are indicated by the reference characters 26 and 27 in Figs. 1a, 3, 4 and 6 and it should be noted that these guides extend forwardly in substantially parallel relation to the bed plate 16, the same being supported on the bed plate by means of the upper and lower brackets 28 and 29 (see Fig. 4).

Before the blanks pass out of the guides 26 and 27 their angled grooves G are engaged by the upper and lower rollers 30 and 31 which have similarly angled working surfaces. However, these rollers 30 and 31 are arranged to extend the legs of the grooves G and thus take in an additional strip of the slit areas on either side thereof. The rollers 30 and 31 are mounted on the shafts 32 and 33 the same being journaled in the uprights 22 similarly to the shafts 20 and 21, including a direct bearing for the shaft 33 and the bearing blocks 34 for the shaft 32 mounted between jaws which are closed or bridged by the members 35 and bolts 36 for tightening the rollers in their gripping position.

Extending forwardly from the working surfaces of the rollers 30 and 31, I have arranged the cooperating guides 37 and 38 having gripping surfaces which gradually change or taper from their entrance ends to their delivery ends in such a manner as to gradually release or uncover the portions of the slit areas which are included in the legs of the angled grooves G of the blanks which they engage. That is, they taper from a configuration substantially the same as that of the grooves as delivered from the rollers 30 and 31 to a configuration substantially as indicated in Fig. 8. Figs. 7 and 8 clearly indicate this change, but it should be observed that these figures are not taken at the extreme ends of the guides, but are taken in section at points intermediate their ends, i. e. substantially at the mid-points of the two sets of upper and lower folding rollers now to be described.

As hereinbefore noted the first set of upper and lower rollers 39 and 40 are positioned at the delivery ends of the guides 26 and 27 and it should be observed that the working surfaces of these rollers are con-

5 figured to grip substantially the entire unslotted areas X of the blanks and fold them up into grooves whose legs extend at substantially right angles to each other. Stated in another way the rollers 39 and 40 deepen and enlarge the relatively shallow beads B by taking in the unslotted areas on each side thereof. The rollers 39 and 40 are mounted on shafts 41 and 42, the same being journaled in the members 22 in exactly the same manner as the shafts 32 and 33 hereinbefore described.

10 The second set of rib forming rollers 43 and 44 are positioned and mounted on shafts 15 45 and 46, the said shafts also being mounted in the manner hereinbefore described. These rollers, as will be seen from inspection of Fig. 8, have working surfaces which fold up the right angled ribs into substantially 20 U-shaped configuration. Short cooperating guides 47 and 48 (see Figs. 1a and 2a 43 and 44). Supporting brackets 49 and 50 are positioned between the sets of rollers 39, 40 and 43, 44, the same serving to support the guides 47 and 48 as well as those numbered 37 and 38.

25 The shafts for the lower sets of rollers, i. e. those numbered 21, 33, 42 and 46 are driven from the main drive shaft 51 thru the intermediate sprocket and chain connection, 52, 53 and 54, with the shaft 46, 30 the other shafts being connected therewith by means of the gears 55 and 56 mounted on the shafts themselves and the idlers 58 and 59 intermeshing therewith. From inspection of Fig. 2a, it will be seen that this gearing arrangement provides a synchronized drive for all of the upper and lower roller shafts.

35 The apparatus for accomplishing the expanding is also mounted on the table 16 and in general consists of a number of pairs of diverging guides and rollers for feeding the blanks therethrough. The receiving ends of the first sets of upper and lower guides 60 and 61 are positioned adjacent to the working surfaces of the rollers 43 and 44 and are adapted to receive and engage the U-shaped ribs of the blanks as they are delivered from the rollers. At this point the cooperating upper and lower guides are supported by 50 means of the supports or brackets 62 and 63 respectively, the same extending transversely of the apparatus between the uprights 22 of the pre-opening apparatus (see Figs. 1a and 4). The other ends of these guides diverge from each other in a horizontal plane and are supported by means of the members 64, 65, the latter being carried by the uprights 69 secured to the table 16 at each side thereof (see Figs. 1a and 2a). Cooperating 55 pairs of upper and lower gripping and feed-

ing rollers are arranged at the delivery ends of the pairs of guides 60, 61, the same being indicated by the reference characters 66 and 67. A shaft 68 serves to support and drive all of the upper rollers 66, the said shaft 70 being journaled at its ends in the standards 69 by means of bearing blocks 70 mounted for vertical movement in the jaws which are formed at the top of the members 69 and which are indicated in Fig. 2a at 71. The 75 upwardly opening jaws 71 are closed by the bridge members 72 and adjusting bolts 73 are provided therein. This journal construction is similar to that described in connection with the shafts 20, 32, 41 and 45 80 with the exception that the adjusting bolts 73 react thru the intermediation of springs 74 instead of directly against the blocks 70. The lower rollers of the cooperating pairs now under consideration are mounted on the 85 shaft 75 which is journaled directly in the members 69.

Extending forwardly from the delivery side of these rollers are other pairs of diverging guides 60, 61 which are similar in 90 all respects to those already described. At their receiving ends they are spaced and supported in a suitable manner by means of the transverse bracket members 76 and 77 while at their other ends they are engaged and 95 supported by members 64 and 65 constructed and supported in the same manner as those previously referred to, provision being made, however, for engagement of the guides 60, 61 at intervals which are farther apart than 100 those at the delivery ends of the first described pairs of guides 60, 61. Feeding rollers and supports are provided at the delivery ends of the second mentioned set of guides and it should be noted that this construction including the uprights 69, shafts 68 and 75 and supporting members 64, 65 and 76, 77, is identical with that already described with the exception that the rollers 105 66 and 67 are more widely spaced and that 110 the guides are arranged to deliver and receive the blanks at the spaced intervals occurring between the rollers.

A third construction of this character is positioned and supported on the table 16 beyond those already referred to and it should be noted that these constructions are spaced longitudinally of the table at substantially equal intervals.

At this point it might be observed that 120 the cross sectional configuration of the guides 60, 61 and the rollers 66, 67 are adapted to engage and maintain the formation of the ribs of the blanks during the expanding operation. Note also that the 125 guides 60, 61 are of special construction in order to reduce wear and facilitate replacements. According to this construction the main bodies of the guides 60, 61 are formed of cast metal, the lower guides 61 having 130

grooves adapted to embrace or engage the ribs and the upper guides 60 being provided with renewable strips or knives 78 (see Figs. 9 to 11 inclusive). These knives 78 are received in suitable longitudinally extending slots in the guides 60 and are secured in position by means of the pins 79, the same preferably being of wedge-like formation in order to ensure tight gripping contact in the openings provided therefor in the guide members 60 and 78. The knives 78 extend into and thus maintain the formation of the ribs during the expanding operation and it should be observed that the knives 78 are preferably made of steel.

The metals here employed, i. e. cast iron and steel, make for the strongest and longest lived guide construction possible. The knives employed must be relatively thin and, therefore, would not be of sufficient strength if made of cast iron, because such metal, as is well known in the art, is relatively brittle. I have constructed these knives, therefore, of steel in order that they may have greater strength, and have constructed the main bodies of the guides 60 of cast iron in order to reduce the cost of production of the parts. The lower guides 61 may be constructed entirely of cast iron in view of the fact that no relatively thin knives or parts are necessary in a guide of grooved formation. Furthermore, the cast iron employed in making the lower members wears very slowly. This construction, therefore, results in inexpensive manufacture as well as longer life of the guide members than was possible heretofore.

Mounted on the table 16 at the delivery ends of the last pairs of diverging guides 60, 61, are supporting members or uprights 80 (see Figs. 1b, 2b, and 11) and supported in these members 80 I have provided a fourth set of upper and lower feeding rollers 66 and 67 mounted on upper and lower shafts 68 and 75 in the same manner as hereinbefore described. The lower shaft 75 in this case is directly journaled in the members 80 while the upper shaft 68 is provided with bearing blocks 70 which are mounted for vertical movement between the jaws 81, the latter being bridged in this instance by means of the members 82. Adjusting bolts 73 and springs 74 are also provided in this instance.

The delivery ends of the guides 60, 61 of the last set are supported by means of the transversely extending supporting members 83 and 84 in position to deliver the ribs of the blanks to the cooperating tongue and groove working surfaces of the rollers 66 and 67. This last or delivering set of rollers feeds the blanks to the straightening guides and rollers located immediately therebeyond. The straightening guides are constructed similarly to those already de-

scribed and from inspection of Figs. 1b and 11, it will be seen that they are again mounted or supported by transversely extending members 85 and 86.

Beyond the guides 87 and 88 in the direction of feed to the apparatus are arranged two upper and three lower straightening roller shafts 89 and 90 respectively, the three lower ones 90 being directly mounted in the uprights 80 and the two upper ones 89 being arranged in staggered relation to the lower ones and being carried by the journal boxes 91 between jaws 92, the latter being closed by means of the binder or bridging member 82. The mechanisms indicated by the reference character 93 serve to adjust the vertical position of the blocks 91.

The upper shafts 89 are provided with straightening rollers 94 having circumferential tongues on their working edges for engaging the interior of the ribs of the expanded sheets while the lower shafts 90 are provided with rollers 95 having circumferential grooves at their working edges for engaging the outside of the ribs.

Each pair of shafts 68 and 75 for the feeding rollers 66, 67 are interconnected by means of gears 96 and 97 (see Figs. 1a, 1b, and 3) and all of the lower shafts 75 are connected to the main drive shaft 51 by means of the chain connections indicated in Figs. 1a, 1b, 2a, and 2b by the reference numerals 98, 99, 100 and 101, each succeeding connection being provided with suitable sprockets 102 keyed to the shafts 75 and 51.

The driving mechanism for the delivering or straightening rollers includes a chain connection 103 between the last of the lower shafts 75 and the first of the straightening roller shafts 90, each of said shafts being provided with a cooperating sprocket wheel 102 (see Figs. 1b and 2b). All of the lower shafts 90 have gears 104 which are interconnected by means of the idler gears 105 all positioned at the side of the apparatus adjacent to the chain driving mechanism. At the other side of the apparatus the upper roller shafts 89 are provided with gears 106 which mesh with a gear 107 keyed to the central lower shaft 90 at the same side of the apparatus. It will be seen, therefore, that the forming rollers 18, 19, 30, 31, 39, 40, 43, 44 and the feeding rollers 66, 67, as well as the straightening rollers 94 and 95 are all driven in timed relation from a single driving shaft, i. e. the shaft 51 which, as shown in Fig. 1a is provided with sprocket wheels 108 for coupling with any suitable source of power.

In considering the operation of the apparatus and also the advantages incident thereto, reference should first be made to the drawings illustrating the pre-opening parts of the mechanism, particularly Figs. 5 to

8 inclusive. When a blank of the character hereinbefore described (see Figs. 12 and 13) is fed into the front end of the machine, its relatively shallow beads B are first engaged by the initial pairs of feeding rollers 18 and 19, the said rollers having working faces of circumferential bead and groove configuration which feed the beads B of the blank and thus serve as guides therefor (see Fig. 5). As the blank is fed forwardly by the rollers 18 and 19, the beads B as well as the unslotted areas on each side thereof are engaged by the cooperating guides 26 and 27. About midway of the guides 26 and 27, the angled grooves G in the center of the slotted areas are engaged by the rollers 30 and 31 which, as already observed, extend the legs of the grooves G and take in an additional portion of the slotted areas. It should be observed that this is accomplished (see Fig. 6) by extending the legs downwardly while maintaining the centers or tops of the grooves substantially within the general plane of the sheet. As shown in Fig. 6 the tops of the angled grooves G are held (by means of the rollers 30 and 31) in the same plane in which the guides 26 and 27 hold the unslotted areas X with their beads B. This operation slightly inclines the portions of the slotted areas which are not taken in by the rollers 30 and 31, the inclination, as will be seen from inspection of Fig. 6, being downwardly from the guides 26 and 27 toward the lower extremity of the legs of the angled grooves G and it might also be noted that this operation very slightly stretches or opens the strands which are not taken in by the rollers 30 and 31. Upon passing thru the rollers 30 and 31 the blank moves forwardly thru the guides 37 and 38 which, as already pointed out, are of a cross-sectional configuration similar to that of the rollers 30 and 31. These guides, as will be seen from inspection of Fig. 4, guide the angled grooves of the blank forwardly until the blank is delivered to the guides 60 and 61 of the expander proper. Two sets of rib engaging and forming rollers 39, 40 and 43, 44 are arranged at successive points along the guides 37 and 38. The first set 39, 40 is adapted to partially fold up the unslotted areas and is positioned along the guides 37 and 38 at a point beyond that at which the guides release a portion of the additional slotted areas which were taken in by the rollers 30 and 31. The release is, of course, gradual from the feeding ends of the guides 37 and 38 to their delivery ends, the same being accomplished by the tapered formation of the guides. This operation will be clear from inspection of Fig. 7 and as will also be apparent from inspection of that figure, the folding up of the unslotted strips X is effected by the rollers 39 and 40 while the bottom or mid points of the strips X are maintained in the general plane of the sheet, i. e. in alignment with the centers of the angled grooves G with the result that the strands S which are not engaged by the guides 37 and 38 are partially opened up. It should be noted at this point that the initial opening operation here accomplished is brought about by a bending of the strands S with respect to the connecting bridges Z by means of an opening pull in a direction transverse of the general plane of the bridges, in contradistinction to an opening pull in a direction in or laterally of the plane of the bridges. Stated in another way, each strand is bent or swung from one end through an arc which lies in a plane substantially at right angles to the connecting bridges Z and, of course, to the legs of the grooves G. The type of opening accomplished by the present apparatus subjects the strands and bridges to the least possible strains and therefore is advantageous in providing a stronger finished product. Note still further in connection with Fig. 7 that the strands S adjacent the unslotted strips are bent or opened with respect to the said unslotted strips in the same manner as the intermediate strands are bent or opened up with respect to their connecting bridges Z. This is accomplished by the partial folding up of the unslotted strips, i. e. to a position in which the slotted areas as a whole extend at substantially right angles therefrom.

The second set of forming rollers 43, 44 is positioned approximately at the ends of the guides 37 and 38 and in view of the fact that the guides progressively engage less and less of the slotted areas at the sides of the angled grooves G, additional strands S are released. These additional strands S are slightly opened up in the manner already described by the additional folding up of the unslotted areas X into the relatively high ribs the same being accomplished by means of the rollers 43 and 44 (see Fig. 8). It should also be observed here again that the centers of the relatively high ribs and of the grooves G are still maintained (by the rollers and guides) in substantially the same plane.

The foregoing pre-expansion or pre-opening operation, it might be noted, should not be confused with the expanding operation proper, i. e. that accomplished by the diverging sets of guides. This pre-opening operation prepares the blanks, so to speak, for the subsequent expanding operation by slightly forming or bending the strands in a manner which subjects them to the least possible strains, and according to which the subsequent expansion or bending of the strands will continue along the same lines as shown in Figs. 9 and 10. It is also worthy

of note that heretofore in this art great difficulty has been experienced in producing lath by means of apparatus employing diverging guides without subjecting the 5 strands of the mesh work to strains which at times even caused breakage during expansion and very frequently resulted in a weak finished article. The underlying cause of this difficulty is the fact that the diverging 10 guides of an expander of the type in question tend to open the strands edgewise in the general plane of the sheet and thus subject the connecting bridges to very great tearing strains. My invention, however, 15 prepares the blanks, for expansion by diverging guides, in such a manner that the bending or opening up of the strands will be carried out with a minimum of tearing strains to the bridges. Thus the apparatus 20 of the present invention permits the use of an expander of the diverging guide type with its incident advantage of high speed production without sacrificing strength in the finished lath.

25 In continuing the discussion of the operation of the apparatus, it should be observed that the last set of rib forming rollers 43, 44, deliver the lath blanks directly to the first set of diverging guides 60, 61, the same being configured to engage and maintain the 30 formation of the relative high ribs. When the forward edge of a blank has passed thru the first set of diverging guides, its ribs are engaged by the feeding rollers 66, 67 and 35 as the blank advances thru the second set of diverging guides, it is engaged by the second set of feeding rollers and so on progressively to the third and last sets, it being borne in mind, of course, that all of the feeding rollers 40 66 and 67 are driven in synchronism. At this point, several advantages of the particular type of expanding mechanism herein disclosed should be noted.

Firstly, the total length of the expander 45 proper is much greater than that commonly provided, i. e. substantially greater than the length of the blanks commonly used and substantially greater than the length of expanders commonly employed in producing a fully 50 expanded lath of a given width. This, of course, enables the guides to be positioned at a very small angle of divergence with the result that the strains to the strands are still further reduced. The small angle of divergence 55 of the guides also permits the use of feeding rollers mounted as shown and described herein, i. e. on shafts or axes of rotation which extend transversely of the guiding mechanism as a whole. Heretofore, when feeding rollers were employed in connection with diverging guides the angle of divergence of the guides was such that the rollers had, of necessity, to be mounted individually on axes extending at right angles 60 to the particular guides with which the

pairs were associated. Stated in another way, as heretofore constructed, each pair of feeding rollers was mounted and arranged so that their gripping surfaces moved in the direction of feed of the blanks thru the particular guides with which the pair was associated. The complication in providing driving connections for feeding rollers mounted in this manner is obviously very great.

I have completely obviated the difficulties just noted by reducing the angle of divergence of the guides to a point which permits the use of sets of feeding rollers mounted for rotation on coinciding or parallel axes 70 the same extending transversely of the expander guides as a whole. All of the upper or lower rollers in a rib engaging set may, therefore, be mounted on a single shaft. The driving connections necessary are, thereby, greatly simplified as is, also, the mounting of the rollers.

Still another advantage of the decreased angle of divergence of the expander guides is the decreased wear and tear to the guides and feeding rollers in general. It is obvious that the feeding rollers must engage the blanks with a much greater pressure in expanders having a relatively great angle of divergence than in expanders in which the angle is diminished. It is also obvious that a greater angle of divergence subjects the guides to proportionately increased lateral wear.

The difficulties which have been noted just above have been particularly troublesome in the manufacture of the so-called "high rib" lath by the diverging guide type of expander in view of the fact that the relatively high ribs must be almost constantly engaged either by guides or rollers throughout the entire length of the expanding mechanism in order to prevent the ribs from opening out or spreading during the expansion process and where the guides have a relatively great angle of divergence the necessary continuous contact of the guides and rollers with the ribs of the blanks resulted in an amount of frictional resistance which was very detrimental to the efficient 100 operation of the mechanism. This difficulty is considerably ameliorated according to the present invention by lengthening out and thus reducing the angle of divergence of the expander guides.

In addition to the advantages already pointed out in connection with the construction of the guide members themselves it should be observed that the provision of the renewable tongue or knife member of each 105 of the upper guides is advantageous as such knives may be replaced, when necessary on account of the wear, without renewing the entire guide member. This, of course, makes for economy in the maintenance of the ap-

paratus and it is worthy of note that the knives may readily be made from standard strip steel stock by cutting the same into suitable lengths and machining the blank 5 engaging edge and ends. Still further an advantage resides in the fact that the renewable knives are the parts of the guides which are subject to the greatest wear. This will be apparent from inspection of Figure 9 or 10 Figure 10 from which it will be seen that the contact and, therefore, the wear on the grooves of the lower guide members 61 is distributed not only on each side of the 15 grooves but also throughout a relatively large area on each of the said sides, whereas practically all of the wear to the upper guides will occur at the bottom edges of the knives 78. The construction, therefore, 20 makes provision for the renewal or replacement of the parts which wear most rapidly. The advantages incident to the use of steel and cast iron in making the knives and the guide bodies have already been noted.

25 The operation of the delivery mechanism including the guides 87 and 88 and the rollers 94 and 95 is quite obvious, the said guides and rollers merely serving to straighten and even up the ribs as they are delivered from the last set of feeding rollers 66 and 67 30 and to deliver the blanks from the apparatus. A portion of a completed blank is illustrated in Figs. 14 and 15 from which it will be observed that the mesh work takes the form 35 of a plurality of inclined diamond-shaped meshes on either side of relatively narrow unslotted strips, the latter originally constituting the central portion of the angled grooves G (see Figs. 12 and 13). It will 40 also be noted that the "diamonds" are inclined in opposite directions on each side of the said relatively narrow unslotted strips and that the strengthening ribs B1 are interposed between each pair of mesh work 45 sections.

45 In conclusion attention should again be directed to the simplicity of the driving mechanism for the various forming, feeding and delivery rollers, the same not requiring the use of any flexible or universal connections whatsoever.

50 The apparatus herein disclosed is described and claimed in my copending application Serial No. 619,186, filed June 25th, 1932.

55 I claim:—

1. The method of pre-opening blanks having a longitudinally extending unslotted area and a longitudinally extending slotted area with a groove therein, which includes 60 gripping the blank at its groove, gradually releasing the portions of the slotted area included in the groove, and slightly opening said portions, as released, by folding up the unslotted area into a relatively deep rib.

65 2. The herein described method of pre-

opening blanks having a longitudinally extending slotted area with a groove therein, which includes extending the legs of the groove to include additional portions of the slotted area on each side thereof while still 70 maintaining the original width of the blank, and slightly opening the strands of the slotted area included in the legs of the groove.

3. The herein described method of pre-opening blanks having a longitudinally extending slotted area with a groove therein, which includes extending the legs of the groove to include additional portions of the slotted area on each side thereof while still 75 maintaining the original width of the blank, and slightly opening the strands of the slotted area included in the legs of the groove, said last mentioned step being carried on progressively beginning with the strands at the extremities of the groove legs.

4. The method of pre-opening blanks having a longitudinally extending slotted area and a groove in the slotted area, the legs of which extend substantially at right angles to each other, which includes extending the legs of the groove to slightly open the strands of the slotted area not included 80 therein, and slightly opening the strands included in the groove the last mentioned step being carried on progressively beginning with the strands at the extremities of the groove legs.

5. The method of pre-opening blanks having a longitudinally extending slotted area which includes forming a groove in the slotted area, the legs of which extend substantially at right angles to each other, slightly opening the strands of the slotted area included in the legs of the groove, the 85 opening operation being carried on progressively beginning with the strands at the extremities of the said legs.

6. The method of pre-opening blanks having a longitudinally extending slotted area which includes forming a groove in the slotted area the legs of which extend substantially at right angles to each other, slightly opening the strands of the slotted area included in the legs of the groove by 90 swinging the same from one end through an arc which lies in a plane substantially at right angles to the legs of the groove in which they are included.

7. The method of pre-opening blanks having a longitudinally extending slotted area which includes forming a groove in the slotted area, slightly opening the strands of the slotted area included in the legs of the groove by swinging the same from one end 95 through an arc which lies in a plane substantially at right angles to the legs of the groove in which they are included.

8. The method of pre-opening blanks having a longitudinally extending slotted area 100

which includes forming a groove in the slitted area, slightly opening the strands of the slitted area included in the legs of the groove by swinging the same from one end 5 through an arc which lies in a plane substantially at right angles to the legs of the groove in which they are included, the said operation being carried on progressively beginning with the strands at the extremities 10 of the legs.

9. In the herein described method of expanding blanks having longitudinally extending slitted areas and longitudinally extending unslitted areas, the steps of folding 15 up the unslitted areas into ribs substantially of the depth and configuration desired in the completed product, and utilizing the said folding up operation to accomplish a pre-opening of the strands of the slitted areas, 20 and subsequently subjecting the blanks to an opening pull substantially in the general plane thereof to complete the expansion.

10. In the herein described method of expanding blanks having longitudinally extending slitted areas and longitudinally extending unslitted areas with grooves in the former, the steps of folding up the unslitted areas into ribs and utilizing the said folding up operation to accomplish a pre-opening 25 of the strands included in the legs of the grooves in the slitted areas.

11. In the herein described method of expanding blanks having longitudinally extending slitted areas and longitudinally extending unslitted areas with grooves in the former, the steps of folding up the unslitted areas into ribs the bottoms of which lie substantially in the plane of the bottoms of the grooves and the legs of which extend oppositely to the legs of the grooves, and slightly 35 opening the strands included in the legs of the grooves in the slitted areas as the folding up operation is carried on.

12. In the herein described method of expanding blanks having longitudinally extending slitted areas and longitudinally extending unslitted areas with grooves in the former, the steps of progressively folding 45 up the unslitted areas into ribs the bottoms of which lie substantially in the plane of the bottoms of the grooves and the legs of which extend oppositely to the legs of the grooves, and progressively slightly opening the strands included in the legs of the grooves in 50 the slitted areas as the folding up operation is carried on.

13. In the herein described method of expanding blanks having longitudinally extending slitted areas and longitudinally extending unslitted areas with grooves in the former, the steps of progressively folding 55 up the unslitted areas into ribs the bottoms of which lie substantially in the plane of the bottoms of the grooves and the legs of which extend oppositely to the legs of the grooves,

and progressively slightly opening the strands included in the legs of the grooves in the slitted areas as the folding up operation is carried on, the last mentioned operation being carried on successively beginning 70 with the strands farthest from the center of the grooves.

14. In the herein described method of expanding blanks having longitudinally extending slitted areas and longitudinally extending unslitted areas with grooves in the former, the step of folding up the unslitted areas into ribs the bottoms of which lie substantially in the plane of the bottoms of the grooves and the legs of which are substantially parallel to the nearest groove legs to slightly open the strands between the ribs and grooves.

15. In the herein described method of expanding blanks having longitudinally extending slitted areas and longitudinally extending unslitted areas with grooves in the former, the step of folding up the unslitted areas into ribs the bottoms of which lie substantially in the plane of the bottoms of the grooves and the legs of which extend oppositely to the groove legs and are substantially parallel to the nearest groove legs to slightly open the strands between the grooves and ribs.

16. The herein described method of making expanded metal meshwork from a metallic blank having strands and connecting bridges which includes slightly bending the strands flatwise and longitudinally with respect to the connecting bridges to partially expand the meshwork, and subsequently completing expansion by subjecting the blank to an opening pull in the general plane thereof.

17. In the herein described method of making expanded metal meshwork from a blank which has been slitted to produce strands and strand interconnecting bridges, the steps of gripping a portion of the strands and bridges, gradually releasing said portion and bending the strands, as they are released, flatwise and longitudinally with respect to the connecting bridges to partially expand the meshwork, and subsequently subjecting the blank to an opening pull in a direction laterally of the plane thereof to complete expansion.

18. The method of expanding a blank having a longitudinally extending slitted area with a groove therein, which includes gripping the blank in an area including its groove, gradually releasing portions of the slitted area included in the gripped portion, 120 slightly opening said portions, as released, by bending the strands to extend (lengthwise) at an angle to the general plane of the blank, and subsequently subjecting the blank to an opening pull in a direction later- 125 130

ally of the plane thereof to complete expansion.

19. The herein described process of expanding the meshwork of a slotted metallic blank having strands and strand interconnecting bridges which lie in planes at least parallel to the general plane of the blank, which includes the steps of slightly opening the meshwork by bending the strands thereof with respect to the connecting bridges so that their longitudinal extension is at an angle to the general plane of the blank so as partially to expand the meshwork, and subsequently subjecting the meshwork to an opening pull substantially within the said general plane of the blank, whereby the second mentioned step completes the expansion of the meshwork by additionally bending the strands in a manner similar to that set forth in the first step, even though the strands and connecting bridges were originally disposed in planes at least adjacent to the general plane of the blank.

25

20. The herein described method of opening expanded metal meshwork in two general operations, which includes, as the first operation, swinging or bending the strands of the meshwork so that the longitudinal axes of the individual strands extend at an angle to the general plane of the original blank, and, as the second operation, completing the expansion of the meshwork by subjecting it to an opening pull in the general plane of the blank.

21. The herein described method of expanding a blank having strands and connecting bridges which consists in subjecting the strands to an opening pull in a direction transverse the plane of the blank to partially separate the strands and then in subjecting the strands to an opening pull in a direction laterally of the plane of the blank to complete expansion.

25
